UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

FUEL FEEDER.

Application filed September 29, 1923. Serial No. 665,632.

This invention relates to feeding mechanism and more particularly to fuel feeding mechanism for supplying coal, or like carbonaceous material, to a gas producer or the like.

One of the principal objects of the invention is to provide an improved form of fuel feeding mechanism which is constructed to automatically control the supply of the fuel to insure maintaining the fuel bed within the producer of uniform depth.

Another object of the invention is to provide apparatus of that character which is so constructed as to uniformly distribute the fuel over the fuel bed.

Other objects of the invention will be apparent from the description thereof set out below when taken in connection with the accompanying drawing.

In the drawing in which like characters of reference designate like parts throughout the several views thereof;

Fig. 1 is a vertical sectional view, diagrammatic in form, of a gas producer equipped with fuel feeding mechanism constructed in accordance with this invention;

Fig. 2 is a fragmentary plan view of the apparatus shown in Fig. 1;

Fig. 3 is a vertical sectional view along the line 3—3 of Fig. 2;

Fig. 4 is a fragmentary plan view showing a modified form of drive for the fuel feeding mechanism;

Fig. 5 is a vertical sectional view along the line 5—5 of Fig. 4, most of the parts being shown in elevation;

Fig. 6 is a fragmentary plan view, diagrammatic in nature, of a producer provided with a different type of fuel feeding mechanism;

Fig. 7 is a vertical sectional view of the type of fuel feeding mechanism shown in Fig. 6, the section being along the line 7—7 of Fig. 6; and

Fig. 8 shows in plan a modified form of control mechanism for the form of apparatus shown in Figs. 6 and 7.

This type of feeding mechanism is capable of general application, but as illustrating a preferred embodiment thereof, it is shown as adapted for the feeding of coal to the generating chamber of a gas producer. The very general practice, nowadays, especially with producers of any considerable capacity, is to so construct those producers that they are mechanically operated throughout, thus

securing the desired uniformity of operation without the necessity of excessive labor costs. In producers of this character the body portion of the producer, which generally contains the fuel bed, and the top portion, which usually carries fuel feeding and agitating mechanism, are so arranged that they may be rotated relatively to each other. In the somewhat diagrammatic showing of Fig. 1, the body portion of the producer is designated generally by the numeral 10, while the top portion is designated generally by the numeral 11. Any desired means for rotating these two parts relative to each other may be utilized, but as shown a very satisfactory way of accomplishing this rotation is to provide the body portion with a toothed rack, 12, the top portion carrying a motor driven pawl 13, which meshes with the rack. As shown the body portion of the producer is held stationary while the top portion is rotated relatively thereto.

With a producer of this character, especially where it is of considerable size, 10 to 15 feet internal diameter for example, the problem of evenly distributing the fuel is somewhat complicated, for considerably more fuel must be distributed toward the outer part of the fuel bed than toward the center thereof in order to secure uniform distribution of the fuel over the whole surface of the fuel bed. As shown particularly in Fig. 2 the fuel feeding mechanism is arranged to one side of a diameter of the producer, and is so constructed that the fuel may be fed at a progressively increasing rate from the center of the producer toward the periphery. This fuel feed, as shown particularly in Figs. 2 and 3, consists of a base member 20, which is provided with a plurality of openings 21, which cooperate with corresponding openings 22 in the top of the producer. Mounted upon the base member is a plurality of housings 25. Each of the passages 21, within the base member 20, has a housing 25 associated therewith, and as shown in Fig. 2 there are three of these passages 21 and three housings 25 associated therewith. These housings are rigidly secured to the base member 20, in gas tight connection therewith, in any suitable way, as by means of bolts, or the like, the precise means not being illustrated.

Opening into the interior of each of the housings 25 is a fuel supply pipe 26, the

other end of which is connected to a fuel supply chamber 27, which is in turn connected to a storage hopper or bin 28, by means of a pipe 29, which has a swivel connection, of conventional form, therein, this construction being desirable so that fuel may be supplied to the fuel feeding mechanism carried by the rotating top of the producer.

10 Beneath each of the housings 25 the base member is cut away as shown at 35 to receive a slide 36 which is of such extent that when in extreme left hand position it completely closes the bottom of the housing 25, and overlies the passage 21, which communicates with the interior of the housing 25, to thus cut off communication between the passage 21 and the interior of the co-operating housing 25. Attached to the bottom face of the slide 36 is a hook member 37, to which is connected one end of a spring 38, the other end of this spring being connected to a second hook member 39, which is carried by some relatively stationary part 20 of the apparatus. As shown this hook 39 is connected to the base member 20, the construction described being such that the spring 38 will tend to urge the slide 36 toward right hand position, to uncover the 25 passage 21, and connect that passage to the interior of the housing 25. The end of the slide 36 extends beyond the base of the housing 25 and is provided with an extension 45, the free end of which carries a roller 46, adapted to cooperate with the face of the cam 47 which is mounted upon the shaft 48. This shaft is shown as direct connected to the motor 49, operation of the motor causing rotation of the shaft 48 and the cams 40 47 carried thereby. Each of these cams 47 is cut away as at 50, the construction being such that during rotation of the cams each slide 36 will be held in extreme left hand position, to close the connection between the 45 passage 21 and the interior of the housing 25, except during such time as the roller 46 cooperates with the cut away portion 50 of the cam associated therewith. As rotation of the cam brings this cut away portion into 50 cooperative relation with the roller the spring 38 will cause movement of the slide to the right. And this will cause the feeding of a charge of fuel through the passage 21. The fuel introduced through the pipe 55 26 will spread itself over the upper surface of the slide 36, within the interior of the housing 25, and will come to rest with its surface assuming a definite angle of repose, this angle being dependent upon the size and 60 character of the fuel. The proportions of the housing, under the base member, are such that when the fuel introduced through the pipe 26 assumes its normal angle of repose it will spread over the slide 65 36 to approximately the edge of the passage

21, but will not, unless forced, run down through the opening 21. When the slide 36 is moved to the right, however, it is moved beneath the fuel resting upon it, since this fuel is constrained against right hand movement by means of the housing. Upon the reverse movement of the slide, to the left, the fuel is carried with it so that that portion of the slide which overlies the passage 21 will have a supply of fuel thereon. Upon another movement of the slide to the right this fuel will drop over the edge of the slide through the passage 21 into the generating chamber of the producer.

As stated above it is necessary during operation to introduce more fuel into the producer adjacent the wall than adjacent the center of the fuel bed. If desired the necessary introduction of fuel into the generating chamber to effect substantially uniform distribution of the fuel over the fuel bed therein may be accomplished by operating each of the slides 36 at a progressively increasing rate from the center to the outer wall of the producer. In the producer of the character shown, having an inside diameter of 12 to 14 feet, if these slides are operated at respective rates of 1:3:5, a substantially uniform distribution over the fuel bed will be secured. But even with such uniform distribution uniformity in the depth of the fuel bed may not be secured for combustion may proceed at a more rapid rate at one portion of the fuel bed than another and consequently one portion of the fuel bed may be consumed more rapidly than another. Therefore means is provided for controlling the functioning of each of the slides 36 so that it will be actuated to cause introduction of fuel to the generating chamber of the producer only so long as the level of the fuel bed to which the particular slide causes the introduction of fuel is below the predetermined and desired normal level.

Pivoted within an opening in the top of the producer adjacent each of the slides 36 is a drag member or finger 60 the lower end of which is adapted to extend down into the generating chamber of the producer a sufficient distance to contact with the surface of the fuel bed therein. The upper end of each pivoted bar 60 is pivotally connected to a link 61, the other end of which is pivotally connected to one arm 62 of a bell crank lever, the other arm, 63, of which serves as a catch or latch member and is so positioned that it may be moved into or out of cooperation with the outer end of the corresponding plate 36. As the level of the fuel bed within the generating chamber rises or falls the end of each of the fingers 60 will correspondingly rise or fall, and through the link 61 of the bell crank lever will be rocked about this pivot 64, to vary the position of the latch 63 so that that latch will permit

free movement of the corresponding slide or restrain that slide from movement to the right. So long as the level of the fuel bed with which any one of the fingers 60 is associated is below the predetermined normal level the latch 63 will be held out of the path of travel of the slide 36 and consequently that slide will be free to reciprocate under the action of the spring 38 and the cam 47. But when the level of the fuel bed rises to the predetermined normal level corresponding rising of the end of the finger 60 will cause movement of the latch member 63 into such position that it will prevent reciprocation of the slide to the right. As shown, particularly in Fig. 2, each of the slide members is provided with a finger and latch mechanism, and consequently uniform distribution of the fuel will be secured, for each slide will continue to function to cause feeding of fuel to the portion of the fuel bed supplied from said slide, until such time as the level of that particular portion of the fuel bed is built up to the desired height, when the latch 63 will be moved to prevent further functioning of the corresponding part of the fuel feeding mechanism.

In order to prevent the escape of gas from the producer through the fuel feeding mechanism into the atmosphere, or from the air through the fuel feeding mechanism into the producer, steam is introduced into the interior of the housing 25 through the pipe 70, this steam serving to prevent the flow of gas from the producer into the housing, where the producer is operated under pressure, and to prevent the flow of air into the producer through the housing, where the producer is operated under suction.

In Figs. 4 and 5 is shown a slightly modified form of mechanism for actuating the slide 36. Keyed to the shaft 48' and rotatable therewith is a sleeve member 80 which carries a clutch member 81. Slidably mounted upon the shaft 48' is a sleeve 82, which carries a second clutch member 83. Also carried by the sleeve 82 is an eccentric 85 which has cooperating therewith an eccentric strap 86, which is in turn connected by means of the eccentric rod 87, to one end of a link 88, the other end of which is connected to the free outside end of the slide 36'. The shaft 48' is rotated continuously by means of a motor, as is also the case with the modification illustrated in Figs. 1-3, and the clutch member 81 is also rotated continuously therewith. By sliding the clutch member 83 into frictional contact with the clutch member 81 the sleeve 82 may be also caused to rotate, with accompanying rotation of the eccentric, to cause backward and forward movement of the slide 36'. Pivotally mounted upon some suitable fixed part of the apparatus, as shown somewhat diagrammatically by the numeral 90 is a bell crank

lever, one arm 91 of which is pivotally connected to one end of the link 61' the other end of the link being connected to the finger 60. The other arm 92, of the bell crank lever is forked at its outer end and cooperates with a groove or cut out portion 93, upon the sleeve 82 so that as the level of the fuel bed within the generating chamber rises or falls the bell crank lever will be rocked to slide the sleeve 82 along the shaft 48' to bring the clutch member 83 into, or out of, frictional contact with the clutch member 81, to thus cause actuation of the slide 36', or to interrupt functioning thereof.

In Figs. 6 and 7 is shown another modified form of fuel feeding mechanism, which is adapted to accomplish the same control of the fuel distribution as is effected by the form of apparatus above described. In Fig. 6, which is somewhat diagrammatic in character, this fuel feeding mechanism is shown to consist of a plurality of bell hoppers which are arranged radially across the top of the producer, in substantially the same general arrangement with reference to the generating chamber of the producer as is the case with the type of apparatus described above. Each of these fuel hoppers, however, is entirely separate and independent of the others; but as the various fuel hoppers are identical in construction, only one of them is shown in detail, a vertical sectional view of one of these bell hopper feeds being shown in Fig. 7.

In that form of apparatus the top 11' of the producer is provided with an opening 100 with which cooperates the base member 100, the depending flange 101 extending downwardly from the base member and terminating within the generating chamber of the producer. Secured to the base member, as by means of bolts or the like, is a bell hopper 102, having an opening adapted to register with the passage within the base member 100, through which fuel passes from the bell hopper into the generating chamber of the producer, and an inlet pipe 103, which is suitably connected to a fuel measuring or feeding device, which in turn comprises a housing 104 having a ported cylindrical plug 105 therein, this plug being mounted upon the shaft 106, the outer end of which carries a pulley, sprocket, or the like 107. This housing has a discharge passage 108, which connects with the inlet passage 103 of the bell hopper and an inlet or supply passage 109, which registers with the fuel supply pipe 110, that pipe in turn being connected to a hopper or bin, as is the case with the pipe 26 described above.

The pulley 107 carries a belt 115, which also rides over a drive pulley 116, mounted upon the shaft of the motor 117, a separate motor being provided for each of the individual fuel feeds, as shown in Fig. 6. During rotation of the motor fuel is fed, by

means of the measuring device into the bell hopper, the passage of fuel from the bell hopper into the producer being controlled by means of the bell or closure 120, which is 5 pivotally connected to the rod 121, the upper end of which passes through suitable backing 122, carried by the upper wall 123 of the bell hopper, and has thereon a piston 124, which is slidably mounted within the cylinder 125, which cylinder is mounted upon, or forms an extension of, the bell hopper 102. Steam is continuously supplied to this cylinder through the pipe 130, which opens 10 into the cylinder below the piston, this pipe 15 of course being provided with any desired type of control valve, which is not shown. Positioned within a suitable opening in the top 123 is a valve casing 131, having a valve 132 therein, which is normally urged toward 20 open position by means of the spring 133. The stem of this valve carries a roller 134 upon the outer end thereof which is adapted to cooperate with the cam 135, mounted upon the shaft 136, of the pulley 137, which 25 pulley is driven by means of the belt 138 from a pulley 139, which is also driven by the motor 117. As the motor rotates it will rotate the pulley 137 and the cam 135. The spring 133 will urge the valve toward open 30 position, bringing the roller 134 against the surface of the cam, and as the cam turns to bring the depression 140 thereof opposite the roller the valve will open under the action of the spring to connect the space within 35 the cylinder 125, beneath the piston, to the interior of the bell hopper thus relieving the pressure within that cylinder and allowing the piston to move downwardly under the weight of the parts connected thereto 40 and the weight of the coal within the bell hopper. The closure 120 will thus also move downwardly, to open the passage within the base member 100 and to allow the fuel within the hopper to pass into the generating 45 chamber of the producer. As the cam continues to rotate the valve 132 will close and the steam pressure will again build up under the piston 124 to raise that piston into elevated position, and again force the closure 50 member against the depending flange 101 to interrupt the passage of the fuel from the bell hopper into the generating chamber of the producer.

Pivotaly mounted within the top is a 55 finger 60", the upper end of which is pivotally connected to the link 61", which is in turn connected to one end 150 of the bell crank lever, the other end 151 of which serves as a latch member to cooperate with 60 the collar 152, upon the stem of the valve 132. As the height of the fuel bed within the producer builds up the finger 60" will 65 actuate the latch 151 to move it into the path of travel of the collar 152 and thus prevent opening of the valve.

As shown the member 105 is adapted to supply fuel to the bell hopper continuously, in small successive charges, and the construction is such that during normal operation of the producer the fuel will not be 70 supplied to the bell hopper at a faster rate than it is needed for replenishing the fuel bed within the generating chamber. But with the construction as shown fuel will be supplied to the bell hopper even though the 75 exhaust valve 132 is held in closed position to prevent the feeding of fuel from the bell hopper into the generating chamber of the producer. It is sometimes found desirable to arrange the mechanism connected with 80 the finger 60" to control the operation of the measuring device 104 as well as the valve 132.

In Fig. 8 is shown a somewhat diagrammatic view of mechanism for accomplishing 85 this. As shown in this figure the two pulleys 116 and 139 which are carried upon a sleeve are preferably integral and loosely mounted upon the shaft of the motor 117, this sleeve having a clutch element 161 thereon which is adapted to cooperate with a clutch element 162 which is slidably mounted on the shaft of the motor. The arm 151' of the bell crank lever, which is actuated by the finger 60" is forked, as described above 95 in connection with the construction shown in Figs. 4 and 5, and upon movement of the finger in response to variations in the level of the fuel bed, the clutch element 162 will be moved along the shaft to bring the two 100 clutch members into or out of contact. When the two clutch members are brought into cooperative relation both the fuel feeding member 104 and the pulley 137 will be rotated to feed fuel to the bell hopper and to, at the same time, open the valve 132, as 105 the cam 135 is rotated, to periodically feed fuel from the bell hopper into the generating chamber of the producer.

As stated above in connection with the 110 modification shown in Figs. 1 through 5 it is not at all necessary that the finger 60", with its cooperating members, be utilized. But probably most satisfactory operation will be secured under the service conditions 115 most generally encountered where this construction is used. The cams 135 may be so arranged that the bell hoppers are operated at a progressively increasing rate from the center of the producer outwardly towards the shell. Or the ratio of the pulleys 137 and 139 may be so arranged that the same progressively increasing rate of feed from the center of the producer out may be secured. Of course in this modification if the 120 finger 60" were dispensed with the clutch mechanism described could also be dispensed with.

While the forms of apparatus herein described constitute preferred embodiments of 125

the invention, it is to be understood that the invention is not limited to these precise forms of apparatus, and that changes may be made in either without departing from the scope of the invention which is defined in the appended claims.

What is claimed is:

1. A gas producer comprising a body portion, constructed to contain a fuel bed, and a top, the body portion and top being rotatable relative to each other; fuel feeding mechanism mounted upon the said top, and means at all times responsive to variations in the fuel level within the body portion for controlling the operation of the fuel feeding mechanism.

2. A gas producer comprising a body portion, constructed to contain a fuel bed, a top therefor, the top and body portion being rotated relative to each other; fuel feeding mechanism carried by said top, means for actuating the said fuel feeding mechanism, and means at all times responsive solely to variations in the level of the fuel within said body portion for controlling the said actuating means.

3. A gas producer comprising a body portion constructed to contain a fuel bed, a rotatable top therefor, fuel feeding mechanism mounted upon said top, means for actuating said fuel feeding mechanism, a pivoted finger mounted upon said top, the lower end of said finger extending downwardly into the body portion of the producer, the construction being such that the lower end of the said finger is adapted to rest upon the upper surface of the fuel bed, and means connecting the upper end of the said finger to the said actuating means, whereby movement of the said finger about its pivot, in response to variations in the level of the fuel bed will throw said actuating means into or out of engagement with the said fuel feeding mechanism.

4. A gas producer, comprising the combination with a body portion constructed to contain a fuel bed and a rotatable top therefor, of a fuel feeding device mounted upon the said top, constantly operating means for actuating said fuel feeding device, and means at all times responsive to variations in the level of the fuel within the said body portion of the producer for connecting or disconnecting said actuating means and said fuel feeding means.

5. A gas producer comprising a body portion constructed to contain a fuel bed, a rotatable top therefor, fuel feeding mechanism comprising a plurality of fuel feeding elements, positioned at varying distances from the axis of rotation of the said top, each element being constructed to supply fuel to a given zone of the said fuel bed, actuating means for the said fuel feeding elements, and means for independently con-

trolling operation of each of the said fuel feeding elements, according to the level of that zone of the fuel bed to which it supplies fuel.

6. A gas producer comprising a body portion constructed to contain a fuel bed, a rotatable top therefor, a plurality of fuel feeders carried by said top, and positioned at varying distances from the center of the producer top, each fuel feeder being constructed to supply fuel to a given zone of the said fuel bed, a common means for actuating each of the fuel feeders, and separate means associated with each of the said fuel feeders, each of the said separate means being responsive to variations in level of the zone of the fuel bed to which its respective fuel feeder is adapted to supply fuel, and means associated with each of the said separate means for operatively connecting or disconnecting its cooperating fuel feeder to the said actuating means.

7. A gas producer comprising the combination with a body portion, constructed to contain a fuel bed, and a rotatable top therefor; of a plurality of fuel feeders, positioned at varying distances from the axis of rotation of the said top, each fuel feeder being adapted to supply fuel to a given zone of the fuel bed; a constantly rotating shaft, a plurality of actuating means mounted upon said shaft, each of said actuating means being associated with one of the said fuel feeders and constructed to cause actuation of its associated fuel feeder, a control finger pivotally mounted within an opening in the top of said producer, its lower end extending downwardly into the producer and being constructed to cooperate with the upper surface of the fuel bed, the other end extending upwardly above the top of the said producer, and means actuated by said finger for operatively connecting or disconnecting the said fuel feeders with the said actuating means upon the rotating shaft.

8. A gas producer comprising the combination with a body portion, constructed to contain a fuel bed, and a rotatable top therefor; of a plurality of fuel feeders, positioned at varying distances from the axis of rotation of the said top, each fuel feeder being adapted to supply fuel to a given zone of the fuel bed, a constantly rotating shaft, a plurality of actuating means mounted upon said shaft, each of said actuating means being associated with one of the said fuel feeders and constructed to cause actuation of its associated fuel feeder, a plurality of control fingers pivotally mounted within an opening in the top of said producer, each of said fingers being operatively associated with one of the said fuel feeders, the lower end of each finger being constructed to cooperate with the upper surface of that zone of the fuel bed with

which its respective fuel feeder is associated, and means connected to the outer end of each of said fingers for operatively connecting or disconnecting the feeder associated therewith and the respective actuating means mounted upon said rotating shaft.

8. A gas producer comprising the combination with a body portion constructed to 10 contain a fuel bed and a rotatable top therefor, having a fuel inlet opening therein; of a fuel feeding mechanism mounted upon said top comprising a base member having a fuel discharge opening therein positioned 15 to cooperate with the fuel feeding opening in the said top, a housing mounted upon said base member, having a fuel receiving opening therein, a conveyor pipe connected to said opening for supplying fuel to the 20 interior of the housing, means for feeding fuel from the said housing through the fuel discharge opening into the said producer said means consisting of a slide or plate, actuating means for causing movement of 25 said plate to effect feeding of the fuel, and means responsive to variations in the level of the fuel bed within the said producer for holding said plate out of operative connection with the said actuating means.
- 30 9. A gas producer comprising a body portion constructed to contain a fuel bed and a rotatable top therefor; a plurality of fuel feeding elements positioned at varying distances from the axis of rotation of the top of the said producer, each element being constructed to supply fuel to a given zone of the said fuel bed, actuating means for the said fuel feeding elements constructed 35 to normally actuate each of the said fuel feeding elements at a predetermined rate which is dependent upon its relative positioning with respect to the center of said fuel bed; and means associated with each 40 of the fuel feeding elements, and responsive to variations in the level of the fuel in the fuel bed, each of which means is adapted to operatively connect or disconnect its respective fuel feeding element according as 45 to the level of fuel in that zone of the fuel bed to which it supplies fuel falls or rises below or above a predetermined level.

- 50 10. In fuel feeding mechanism for a gas producer, or the like, comprising a body portion constructed to contain a fuel bed and a rotatable top therefor; a plurality of fuel feeding elements mounted upon said top, and positioned at varying distances from the axis of rotation of said top, each 55 element comprising a base member having a fuel discharge opening therein positioned to cooperate with a fuel feeding opening in the said top, a housing mounted upon each said base member and having a fuel receiving opening therein constructed to receive a

conveyor pipe connected to a suitable source of supply for supplying fuel to the interior of said housing, a sliding plate within each of said housings; a constantly rotating shaft adjacent the said several fuel feeding mechanisms, means carried by said shaft and each of the said fuel feeding elements for causing sliding movement of each of the said plates to feed fuel from within the said housings onto the fuel bed of the producer, the said means being so constructed as to operate the respective fuel feeding elements at variable rates according to the position of each of the said elements with respect to the center of the fuel bed; and means associated with each of the said fuel feeding elements, and independent of the other fuel feeding elements, for rendering inoperative the actuating means associated with its respective fuel feeding elements without affecting the operation of the other fuel feeding elements.

11. In fuel feeding mechanism for a gas producer, or the like, comprising a body portion constructed to contain a fuel bed and a top therefor, the body portion and top being relatively rotatable; a fuel hopper having a discharge opening through which fuel may pass from said hopper into the interior of the producer, a reciprocable closure member for said hopper, means for normally opening said closure member at predetermined intervals to permit the passage of fuel through the said discharge opening, and means at all times operatively responsive to the level of the fuel bed with which said fuel feeding mechanism is associated for rendering the said operating means inoperative.

12. A gas producer comprising a body portion constructed to contain a fuel bed, a top therefor, fuel feeding mechanism for said producer, control means for controlling the operation of said fuel feeding means, and means for actuating said control means, said control means being at all times responsive solely to variations in the fuel level within said body portion.

13. In fuel feeding mechanism for a gas producer, or the like, comprising a body portion constructed to contain a fuel bed and a top therefor, said top and body portion being relatively rotatable; a fuel receiving hopper having a discharge opening connecting the interior of said hopper to the interior of the producer, means for introducing fuel into said hopper, a closure member for said discharge opening, a pressure operated piston for holding said closure member in closed position and means associated with said pressure operated piston for opening said closure member at predetermined intervals.

14. In fuel feeding mechanism for a gas producer, or the like, comprising a body portion constructed to contain a fuel bed and a top therefor, said top and body portion being relatively rotatable; a fuel receiving hopper having a discharge opening connecting the interior of said hopper to the interior of the producer, means for introducing fuel into said hopper, a closure member for said discharge opening, a pressure operated piston for holding said closure member in closed position and means associated with said pressure operated piston for opening said closure member at predetermined intervals.

15. In fuel feeding mechanism for a gas producer, or the like, comprising a body

portion constructed to contain a fuel bed and a top therefor, said top and body portion being relatively rotatable; a fuel receiving hopper having a discharge opening connecting the interior of said hopper to the interior of the producer, means for introducing the fuel into said hopper, a closure member for said discharge opening, a pressure operated piston for holding said closure member in closed position, means for relieving the pressure on the said piston to permit opening of said closure member, and means responsive to the level of the fuel bed within the producer for rendering said pressure relieving means inoperative.

16. In a fuel feeding mechanism for a gas producer, or the like, comprising a body portion constructed to contain a fuel bed and a top therefor, said top and body portion being relatively rotatable; a fuel receiving member having a discharge opening connecting the interior of said member to the interior of the body portion of the producer, means for introducing fuel at a predetermined rate into the interior of said receiving member, a closure for said discharge opening, a pressure cylinder associated with said receiving member, a piston within said cylinder, a piston rod connecting the said piston to the said closure member for actuating said closure member, means for continuously introducing pressure fluid into the said cylinder to urge the piston in one direction to maintain the closure member in closed position, a valve controlled discharge passage within said cylinder, means for actuating said valve at predetermined intervals to relieve the pressure on the said piston with resultant opening of the said closure member, and means responsive to the level of the fuel within the fuel bed for preventing opening of said discharge valve so long as the fuel level is above the predetermined level.

17. In a fuel feeding mechanism for a gas producer, or the like, comprising a body portion constructed to contain a fuel bed, a top therefor, the top and body portion being rotatable relative to each other; fuel feeding mechanism carried by said top, actuating means for said fuel feeding mechanism, control means responsive to variations in the level of the fuel within said body portion for controlling the said actuating means, said control means having provisions for automatically starting said actuating means when the level of the fuel falls below a predetermined point, and for automatically stopping said actuating means when the level of the fuel rises above a predetermined point.

In testimony whereof I hereto affix my signature.

HARRY F. SMITH.
